W. A. MITCHELL.
DRAFT YOKE FOR RAILWAY CAR DRAFT RIGGING.
APPLICATION FILED FEB. 17, 1913.

1,128,347.

Patented Feb. 16, 1915.

FIG. 1

UNITED STATES PATENT OFFICE.

WILLIAM A. MITCHELL, OF SEDALIA, MISSOURI, ASSIGNOR TO WILLIAM H. MINER, OF CHICAGO, ILLINOIS.

DRAFT-YOKE FOR RAILWAY-CAR DRAFT-RIGGING.

1,128,347.

Specification of Letters Patent.

Patented Feb. 16, 1915.

Application filed February 17, 1913. Serial No. 748,794.

To all whom it may concern:

Be it known that I, WILLIAM A. MITCHELL, a citizen of the United States, residing at Sedalia, in the county of Pettis and State 5 of Missouri, have invented a certain new and useful Improvement in Draft-Yokes for Railway-Car Draft-Rigging, of which the following is a full, clear, concise, and exact description, reference being had to 10 the accompanying drawing, forming a part of this specification.

My invention relates to improvements in draft yokes for railway car draft rigging, and more particularly yokes for railway 15 passenger car draft rigging.

The object of my invention is to provide a draft yoke of durable construction and efficient operation.

In the drawings forming a part of this 20 specification Figure 1 is a side elevation, partly in vertical longitudinal section on line 1—1 of Fig. 2 of a draft yoke embodying my invention. Fig. 2 is a plan view, partly in horizontal longitudinal section on 25 line 2—2 of Fig. 1. Fig. 3 is an enlarged detail perspective view of the front portion of the draft yoke. Fig. 4 is a perspective view of one of the bushings.

Referring to the drawings 5 represents 30 the draft yoke, 6 the coupler extension bar, and 7 the connecting pin. The draft yoke comprises a strap like member 8 of a general U-shape, having upper and lower limbs 9 and 10 respectively, and a member 11 connecting said limbs at their rear ends. The 35 filler block 12 is preferably integral with the strap like member 8, and with the member 11 is I-shaped in longitudinal section, as illustrated at the numeral 12 in Fig. 2 of the 40 drawings.

Rearwardly of the forward free ends 13, 18 of the strap like member 8, as indicated at the numerals 14, 14, the limbs 9 and 10 are turned inwardly toward each other, 45 forming the oblique portions 15, 15, forwardly of which the said limbs are again disposed in substantially parallel arrangement, and suitably spaced apart to form the slot 16, which is adapted to receive the coupler extension bar 6. The portions of the 50 limbs of the yoke forming said slot are provided with vertical perforations 17, 17, each adapted to receive a bushing 18. The bushings 18 are each provided with an outwardly 55 extended flange 19, which serves to secure

the bushing against accidental displacement. The pin 7 passes through the said bushings and through the perforation 20 in the butt 21 of the coupler extension 6. The rear face 22 of the butt of the coupler extension 60 is preferably convexly curved in vertical plane, and is adapted to engage the forward concave face 23 of the brace 24. The brace 24 is substantially I-shaped in horizontal section, and comprises a forward plate 25, a 65 rearward plate 26, and a connecting web 27. The said brace 24 is preferably a unitary structure, and integral with the limbs of the yoke. The forward plate 25 of said brace forms the rear wall of the slot 16, and 70 joins together the limbs of the yoke at the forward ends of the oblique portions 15, 15. The rearward plate 26 joins together the two limbs of the yoke at the rearward ends of the oblique portions 15, 15, and at the 75 points indicated by the numerals 14, 14. The connecting web 27 joins together the oblique portions 15, 15 of the limbs as well as the plates 25 and 26.

Between the brace 24 at the front end 80 and the filler block 12 at the rear end of the yoke, and the two limbs 9 and 10 is provided the opening 28, which is adapted to receive a draft gear and followers. The pin 7 is provided at its upper end with a 85 head 29, and at its lower end with the nut 30 threaded thereon, the same being secured against accidental displacement by the cotter pin 31.

It will be apparent that through the construction of the forward end of the yoke hereinbefore described there is provided a vertically narrow slot 16 for the coupler extension bar to engage in, and thus a comparatively short pin 7 is required. By 90 reason of the short pin great strength of connection is assured. Through the engagement of the rear end of the draw bar extension with the brace 24, in buffing movement of the parts, the pin 7 is not subjected to strain, and because of this in connection with the employment of the bushings 18 a 95 minimum wear of the pin and the perforations receiving it is effected.

The shape of the forward ends of the 100 limbs of the yoke in connection with the I-shaped brace very highly strengthens against the spreading tendency of the limbs, and prevents undue stress at the forward 105 ends of the yoke member. Also, the I-shaped 110

- brace insures against the tendency of the limbs to draw together in service, and bind the front follower disposed between them. In this construction pulling stresses to 5 which the limbs back of the brace are subjected are transferred in straight lines, a straight pull is given the forward ends of the yoke limbs, and the pin 7 is subjected to a straight shearing movement.
- 10 I am enabled by reason of the construction described to easily remove the pin 7 from above, while the yoke is in place in the draft rigging of a railway car, through the employment of a short pin, and by 15 reason of the greater space provided between its head and the parts of the car above the same. Further, I am enabled to place the upper limb of the yoke higher in relation to the car frame, thereby enabling

the placing of the yoke above the truck frame. This is of special advantage in cars of low draft. The effective strength of this yoke in transferring the shocks transmitted by the coupler extension to the front follower and draft gear within the yoke directly through the I-shaped brace will be readily understood.

I claim;—

A draft yoke comprising a pair of limbs, a transverse slot between said limbs at one 30 end, a member near either end connecting said limbs, each of said members being I-shaped in horizontal section.

WILLIAM A. MITCHELL.
